UNITED STATES PATENT OFFICE

115,683

DESIGN FOR A BUILDING STRUCTURE

Kenneth E. Bemis, Oakland, Calif.

Application December 7, 1938, Serial No. 81,631

Term of patent 14 years

To all whom it may concern:

Be it known that I, Kenneth E. Bemis, a citizen of the United States, residing at Oakland, in the county of Alameda and State of California, have invented a new, original, and ornamental Design for a Building Structure, of which the following is a specification, reference being had to the accompanying drawing, forming part thereof.

Fig. 1 is a front elevation of a building structure, showing my new design.

Fig. 2 is a top plan view of Fig. 1.

Fig. 3 is an elevation of one end.

Fig. 4 is an elevation of the other end, of my new design.

Fig. 5 is an enlarged fragmentary view showing the locomotive end of the building.

Fig. 6 is an enlarged fragmentary view showing the observation car end of the building.

Fig. 7 is an enlarged fragmentary rear elevation showing the projecting portion of the locomotive end of the building, the front elevation being similar in design.

Fig. 8 is an enlarged fragmentary rear elevation showing the projecting portion of the observation car end of the building, the front elevation being similar in design.

I claim:

The ornamental design for a building structure, as shown and described.

KENNETH E. BEMIS.
